[57] CLAIM

The ornamental design for a swing, as shown and described.

DESCRIPTION

FIG. 1 is a front perspective view of the swing showing our new design;

FIG. 2 is an end elevational view, the opposite end being a mirror image thereof;

FIG. 3 is a front elevational view;

FIG. 4 is a rear elevational view;

FIG. 5 is a top plan view; and,

FIG. 6 is a bottom plan view thereof.

The broken line showing of a backrest headboard is for illustrative purposes only and forms no part of the claimed design.

1 Claim, 6 Drawing Sheets
